(57) **CLAIM**

The ornamental design for an audio and video apparatus for reproducing sounds or images as shown and described.

DESCRIPTION

FIG. 1.1 is a front elevational view of an audio and video apparatus for reproducing sounds or images showing our new design;

FIG. 1.2 is a left side elevational view thereof;

FIG. 1.3 is a right side elevational view thereof;

FIG. 1.4 is a rear elevational view thereof;

FIG. 1.5 is a bottom plan view thereof;

FIG. 1.6 is a top plan view thereof;

FIG. 1.7 is an upper, front, right-side perspective view thereof; and

FIG. 1.8 is a lower, rear, left-side perspective view thereof. The broken lines shown in the drawings are for the purpose of illustrating portions of the audio and video apparatus for reproducing sounds or images that form no portion of the claimed design.
